STAPLING MACHINE

Seraphine F. Bauwens, Chicago, Ill., assignor to
Bauwens Machine Company, Inc.

Application March 23, 1939, Serial No. 263,637

11 Claims. (Cl. 1-3)

The invention relates to improvements in machines for operating on hat bands or the like, and has particularly to do with machines forming decorative bows on such bands. A hat band of this general character is disclosed in my copending application No. 118,205 filed December 30, 1936 now Patent No. 2,166,337, issued July 18, 1939.

In said copending application I have disclosed a hat band or ribbon which is adapted to be attached to a hat by means effective to hold the band securely in place and yet permit it to be removed quickly and easily for purposes of cleaning or replacement. Integral with or attached to the band is a decorative bow conveniently formed by folding a portion of the ribbon material back upon itself and permanently securing it in place as by stapling or the like.

The general object of the present invention is to provide a machine for folding a portion of a hat band or the like to form a decorative bow of attractive appearance and for securing the main portion of the band and the bow in permanent relationship as by stapling.

Another object of the invention is to provide a stapling machine embodying a novel form of mechanism for folding a band as, for example, in the form of a wedge shaped fold or dart, and for stapling the band while so folded.

The invention also resides in various structural improvements in the machine by virtue of which ruggedness and low cost of construction are combined with ease of manipulation and effectiveness of operation.

Further objects and advantages of the invention will become apparent as the following description proceeds, taken in connection with the accompanying drawings in which:

Figure 1 is a bottom perspective view of a hat band folded and stapled by the machine herein disclosed as embodying the invention.

Figs. 2 and 3 show a combined hook and staple before and after being applied to a hat band by the machine herein disclosed.

Fig. 4 is a side elevation of a stapling machine embodying the invention.

Fig. 4^a is a side elevation partly in section of a treadle mechanism adapted to be used with the machine of Fig. 4.

Fig. 5 is a detail vertical sectional view along the line 5-5 of Fig. 4.

Fig. 5^a is a stop motion view of the parts shown in Fig. 5 illustrating particularly the position of the clinching dogs upon completion of an operating cycle.

Fig. 6 is a detail perspective view of the clinching dog carrier included in the device of Fig. 5.

Fig. 7 is a top perspective view of the portion of folded and stapled band shown in Fig. 1.

Fig. 8 is a front elevation of the machine of Fig. 4.

Fig. 9 is a partial rear elevation of the machine of Fig. 4.

Fig. 10 is a partial plan view of the machine shown in Fig. 4.

Fig. 11 is a detail end view of the band folding mechanism included in the machine of Fig. 4 and showing the same in position for starting the folding operation.

Fig. 12 is an end view of the ribbon folding mechanism similar to Fig. 11 but showing the various parts in the positions occupied at the end of the folding operation.

Fig. 13 is a detail vertical sectional view along the line 13-13 of Fig. 8.

For purposes of exemplification the invention has been shown and described herein as embodied in a machine having ribbon folding mechanism and stapling mechanism, the latter acting to drive a staple 10 (Fig. 2) through a dart or fold 11^a formed in a hat band 11 by the folding mechanism. In the particular embodiment illustrated a transverse fiber stiffening strip 12 is secured to the ribbon by the staple. It should be understood that machines embodying the invention are, however, suitable for use in a wide variety of other ribbon folding operations. Accordingly, even though a particular embodiment of the invention has been shown and described in some detail there is no intention to thereby limit the invention to such embodiment, but, on the other hand, the appended claims are intended to cover all modifications falling within the spirit and scope of the invention.

Briefly stated, the stapling mechanism of the machine herein described, is adapted to bend the U-shaped wire staple blank 10, of the form shown in Fig. 2, into the completed tie hook form of Figs. 1 and 3 while applying it to some such article as the hat band 11 and the stiffener strip 12. The staple blank 10 is of U-shape and includes two legs 10^a and 10^b, the leg 10^a preferably having a swaged point so that it will not tear the fabric to which it is later hooked. When applied to the hat band 11 (Figs. 1 and 3) the leg 10^b is flattened or clinched against the face of the reinforcing fiber strip 12 so that the staple and strip are clamped firmly to the hat band. Furthermore, this staple also serves to hold the dart or wedge shaped fold 11^a in place in the band

(see also Fig. 7 for shape of fold). The other staple leg 10^b is curved toward the first leg 10^a (Fig. 13) but is spaced from it. When the leg 10^a is bent into the hook shape shown in Fig. 3 it serves as an effectual means for removably attaching the band to a hat by simply inserting the pointed hook into the fabric of the hat.

The tie hook above described and the die mechanism for bending it to the form shown for the subject matter of a separate application, namely, application Serial No. 310,898 filed December 26, 1939, in which these features of the invention are fully described and claimed.

In the particular machine illustrated (Fig. 4) the folded portion 11^a of the hat band 11 , with the reenforcing strip 12 in place beneath it, is received on a platen formed in part by a horizontal plate 13 carried by a machine frame or bed 14 . Registering with an aperture 15 in the plate 13 is a die unit designated generally by the numeral 16 . In brief, the hat band 11 and fiber strip 12 are clamped in superimposed relation on the die unit 16 by a pivoted stapler head 17 and a plunger 18 on the stapler head thrusts a staple 10 downward so that both of its legs 10^a and 10^b pierce the hat band 11 and fiber strip 12 . As the staple is driven into the hat band and strip, the die unit 16 automatically clinches the staple leg 10^b against the underside of the material and bends the staple leg 10^a into the configuration of Fig. 3.

The stapler head 17 (Fig. 4) embodies a pair of sheet metal side plates 19 (see also Fig. 8) fashioned as integral extensions on the side plates of a supporting arm 20 , which is pivoted on the machine frame 14 by a pin 21 . Suitable transverse pins 22 join the head side plates 19 . The lower edges of the side plates are notched at 23 to receive the fiber strip 12 and hat band 11 , which are placed beneath the head 17 on the die unit 16 . A compression spring 24 normally urges the stapler head supporting arm 20 to its upper or inactive position. To swing the arm 20 and its attached stapler head 17 downward into clamping position, a pivoted treadle 25 (Fig. 4^a) is depressed. A vertical link 26 pivoted on the arm 20 at 27 (Fig. 4) serves to connect the treadle 25 with the arm 20 . The lower end of this link 26 extends through an aperture 28 in the treadle (Fig. 4^a) and has an enlarged head 26^a engageable by the treadle only after it has been depressed a predetermined distance. The purpose of this lost motion connection between the treadle and connecting link 26 is to accomplish a proper timing of the movement of the stapler head 17 with relation to certain other parts of the machine which are also actuated by the treadle 25 , as will hereinafter appear in greater detail.

To drive the staples 10 after the stapler head 17 has been moved downward into clamping position, the plunger 18 is thrust axially downward. For this purpose a hand lever 29 (Fig. 4) is mounted for swinging movement on a rock shaft 30 carried by an upright bracket 31 on the machine frame 14 . The plunger 18 is yieldably retained in its retracted or inoperative position by a helical compression spring 32 . When the lever 29 is swung downward a wear plate 33 on it contacts the head of the plunger 18 so that the plunger is pushed downward and engages one of the staples 10 , driving its legs 10^a and 10^b down through the band 11 and fiber strip 12 . A reserve supply of the staples 10 is carried in a magazine (not shown) housed in the arm 20 and sta-

pler head 17 . The magazine may be of any one of a number of well known forms heretofore available in stapling machines and serves in general to present a fresh staple to the driving plunger 18 upon each successive actuation.

Upon being driven through the folded portion of the hat band 11 and fiber strip 12 the staple legs 10^a and 10^b are received and properly bent by the die unit 16 . This unit (Fig. 4) embodies a horizontal channel shaped frame 34 screwed to the machine frame 14 . Vertically slidable within a notch 35 in the upper leg of the channel frame 34 is a die carrier 36 . This carrier is generally rectangular in form (Fig. 6) and includes a body member 37 having a notch or recess 39 in one side face thereof and across which extends a face plate 38 , fixed to the body member. A pair of helical compression springs 40 underlie the carrier 36 and yieldably urge it upward to the position of Fig. 5 in which the top of the carrier projects somewhat above the level of the plate 13 . Ears 37^a on the end of the carrier limit its upward movement.

Within the recess 38 in the die carrier 36 are mounted a pair of dogs 41 and 42 on pivot pins 43 and 44 respectively. These dogs are shaped and located so that as the staple legs 10^a and 10^b emerge from the lower side of the fiber strip 12 they are engaged by the respective dogs and deflected toward each other in the course of their emerging movement from the strip. After the staple 10 has been driven home the downward movement of the plunger 18 continues a short distance so that the spring urged die carrier 36 is depressed (to the position of Fig. 5^a) and as an incident to the downward movement of the carrier the dogs 41 — 42 are swung upward about their respective pivots to complete the requisite clinching and bending of the respective staple legs.

In particular, the dog 41 has a concave curved upper surface 41^a adapted to engage and bend the staple leg 10^a into the shape shown in Fig. 5^a while the other crimping dog 42 has a generally flat upper surface 42^a which deflects and crimps the second staple leg 10^b . The dog 42 rests on the dog 41 but is maintained sufficiently elevated by the high point on the latter at the end of the curved surface 41^a that it does not interfere with the staple leg 10^a . In turn, the dog 41 rests on a fixed abutment 45 . Consequently, when the die carrier 36 moves downward, due to the pressure of the plunger 18 , the abutment 45 causes the dog 41 to swing upwardly in a counterclockwise direction (as viewed in Figs. 5 and 5^a) and, accordingly, the dog 41 causes the abutting dog 42 to swing upwardly in opposite or clockwise direction. In this manner the staple legs 10^a and 10^b are bent accurately and with precision into the exact finished shape desired (Figs. 5^a and 3). Particularly notable here is the fact that at the termination of the staple leg bending operation the upper surface of the dog 42 is substantially horizontal so that the staple leg 10^b is bent or clinched at a precise right angle without any bulging at the point of bending.

An important feature of the machine is the folding mechanism for forming the wedge shaped fold 11^a (Fig. 7) in the hat band 11 , as an incident to the stapling operation. In general, the dart 11^a is formed by slipping the edge of the hat band 11 into the slotted nose 46 of a rotatable arm 47 (Figs. 8 and 11), rotating the arm through substantially 270° to the position

of Fig. 12 and finally withdrawing the nose 46 from engagement with the band while clamping the folded portion by the stapler head 11 (Fig. 13). For this purpose the arm 47 is mounted for rotation about its own axis to accomplish the necessary twisting or folding of the band and is also mounted for swinging movement from the inactive or elevated position shown in full lines in Fig. 8 to the active position shown in dot-dash lines in such figure. Furthermore, the arm 47 is arranged for axial shifting movement to the retracted position of Fig. 9 to which it is shifted in order to clear the stapler head 11 when the latter is in its clamping position.

The fold forming arm 47 has been shown herein (Figs. 8 to 10) as an elongated flat sheet metal strip secured to the outer end of a shaft 48. This shaft is journaled for rotation in a housing or block 49 which is pivotally supported by a pin 50 fixed to it and journaled in a generally upright link 51 so that the arm 47 may be tilted between its upper and lower positions shown in Fig. 8. The link 51 is in turn pivoted on the machine frame 14 by a transverse pin 52 so that it may be tilted from the upright position of Fig. 8 to the retracted position of Fig. 9 to withdraw the arm 47 from engagement with the folded hat band 11. A contractile spring 53, anchored at its opposite ends to the link 51 and to the machine frame 14, urges the link in a counterclockwise direction (as viewed in Fig. 8), and a stop pin 54 limits its movement in such direction so that the link is yieldably maintained in upright position.

Both rotative movement of the arm 47 and downward swinging movement of this arm are yieldably resisted by a single biasing means in the form of a counterbalancing weight 55 (Fig. 8). This weight is connected to the shaft 48 by a flexible cord or chain 56 which is anchored to the periphery of a grooved pulley 57 fast on the shaft. The pulley is located at a substantial distance, axially of the shaft 48, from the center of the pivot 50 so that the weight 55 tends to swing the arm 47 to its elevated or inactive position. Such upward movement of the arm is limited by a stop projection 58 screwed to the top of the link 51 and engageable with the housing block 49. Similarly the weight 55 serves to hold the arm 47 in a generally vertical edgewise position and yieldably resists rotation of the arm in a counterclockwise direction (as viewed from the slotted nose end of the arm) since during such rotation the cord 56 is wound on the pulley 57 with a consequent elevation of the weight 55. As herein shown, the normal position of the arm 47 is determined by a stop pin 57^a (Fig. 8) carried on one face of a member 61 fast on the shaft 48, the pin engaging one side of an abutment 58^a projecting from the adjacent face of the housing 49.

In order to hold in place the fiber strip 12 while the hat band 11 is being folded a clamp plate or finger 13^a (Fig. 5) is utilized. This clamp plate is pivoted on a pin 13^b and is urged into clamping position by a torsion spring 13^c, which encircles the pin 13^b.

To actuate the folding mechanism described above the operator depresses the treadle 25 (Fig. 4^a) so that a downward tension is exerted on a flexible connecting cord or chain 59, which is yieldably connected at its lower end to the treadle by means of a tension spring 60. The upper end of this cord (Fig. 8) is fixed to the member 61 which in this instance is formed with a peripheral groove 61^a (Fig. 9) for the recep-

tion of the cord. The cord 59 is wound about substantially 270° of the periphery of the member 61 (Fig. 11), when the mechanism is in its initial position shown in full lines in Fig. 8. Consequently, when the treadle 25 is first moved downward the resultant tension in the cord 59 swings the arm 47 downward to the dot-dash line position of Fig. 8. During this downward swinging of the arm 47 its rotation is resisted by the biasing weight 55. After the arm 47 has been depressed the operator slips the edge of the hat band 11 into the slotted nose 46 of the arm 47. Further downward tilting of the arm 47 is prevented by contact of a stop projection 62 (Fig. 9) with a fixed abutment or pin 63. The stop projection 62 is clamped on the pin 50, which is fast in the shaft housing block 49, so that the stop projection swings with the arm 47. Further depression of the treadle 25 then causes the cord 59 to unwind from about the member 61 in the direction of arrow 59^a in Fig. 12 and thus rotate the arm from the vertical edgewise position of Fig. 11 through approximately 270° to the horizontal edgewise position shown in Fig. 12. Rotation of the arm beyond this horizontal position is prevented by engagement of the stop pin 57^a with the opposite sides of the abutment 58^a as shown in Fig. 9. In the course of this rotation the other cord 56 is partially wound about its pulley 57 so that the biasing weight 55 is elevated. After the fold 11^a has been formed in the hat band 11 in the manner described above, further depression of the actuating treadle 25 causes the link 26 to be pulled down so that the stapler head 11 is swung into clamping position as previously described. In this way the hat band 11, with its fold properly formed in it, is clamped against the fiber strip 12 which is in turn seated on the top of the die unit 16.

In order to retract the arm 47 out of engagement with the folded and clamped hat band 11 so that the staple may be inserted therein, an actuating cam 64 (Figs. 8 to 10) is provided on the shaft 30 which carries the stapling plunger actuating lever 29. As the lever 29 is swung downward (Fig. 4) the cam 64 engages a cam projection 65 (Figs. 9 and 10) fixed to the tiltable link 51 and cams this projection 65 out of the path of the actuating cam 64 so that the link 51 is tilted into its retracted position shown in Fig. 9. In this way the arm 47 is withdrawn in timed relation with the staple driving movement of the plunger 18. Since the surface of the stop projection 62 (Fig. 9) is curved, as indicated at 62^a, the arm 47 does not rise as it is retracted but remains at the same angle to the horizontal. By thus retaining the arm 47 depressed as it is retracted, any interference between the arm and the stapler head is prevented.

At the completion of the staple driving operation the actuating treadle 25 and lever 29 are released so that the parts return to their initial position under the action of their respective biasing springs and weight.

In the operation of the machine described above, the operator places the element to be secured to the band such as the fiber strip 12 on the top of the die unit 16, clamps it in position with the clamp 13^a, and lays the hat band 11 loosely in place on top of it. Then the operator depresses the treadle 25 sufficiently to swing the arm 47 downward from the full line position of Fig. 8 to the dot-dash line position shown in such figure. Thereupon the operator slips the edge of the hat band 11 into the notched nose

46 of the arm and then further depresses the treadle 25. This further depression of the treadle causes the arm to be rotated from the position of Fig. 11 to that of Fig. 12 so that the wedge shaped fold 11^a is formed in the hat band 11 (Fig. 7).

Upon completion of the folding operation described above the operator continues the downward movement of the treadle 25 so that it pulls down on the link 26 and thereby swings the stapler head 17 downward to clamp the folded hat band against the fiber strip 12. Thereafter the lever 29 is actuated by rocking it downwardly or in a clockwise direction as viewed in Fig. 4. In the initial movement of the lever the cam 64 acts to retract the dart folding arm 47 to the position shown in Fig. 9, thus moving it free of the clamped ribbon and out of the stapling mechanism. Continued movement of the lever depressing the staple driving plunger 18 which drives the staple 10 through the folded ribbon and stiffening member 12, the die unit 16 acting to bend the staple leg 10^a into the hook form illustrated and to clinch the leg 10^b against the under side of the stiffening member to permanently secure the formed ribbon and member together.

I claim as my invention:

1. A stapling machine comprising, in combination, an elongated arm rotatable about its longitudinal axis and having a slender nose portion transversely slotted to receive the edge of a piece of fabric inserted therein, means for rotating said arm to form a transverse wedge shaped fold in the fabric, and means for clamping the folded fabric and for stapling the same.

2. A stapling machine comprising, in combination, a rotatable member presenting a transverse recess in an outer end thereof adapted to receive the edge of a piece of fabric inserted therein, means for rotating said member to form a transverse fold in the fabric, and means for stapling the portion of the fabric folded by said member.

3. A stapling machine comprising, in combination, a rotatable member presenting a transverse recession in an outer end thereof adapted to receive the edge of a piece of fabric inserted therein, means for rotating said member to form a transverse fold in the fabric, clamping means for clamping the folded fabric, means for withdrawing said rotatable member from engagement with the folded fabric, and means for stapling the folded fabric while it is held in position by said clamping means.

4. In a machine of the class described, the combination with movable staple driving means and cooperating staple clinching means, of an elongated arm supported at one side of the driving and clinching means for rotation about an axis extending longitudinally thereof and for endwise movement, said arm having a slotted nose portion adapted to be interposed between the driving and clinching means to receive the edge of a piece of fabric, means for rotating said arm to form a fold in the fabric, means for advancing said staple driving means toward said staple clinching means to staple the fold to the body of the fabric, and means operated in timed relation to the advance of the staple driving means for imparting endwise movement to the arm to withdraw the nose portion thereof from the fold.

5. In a machine of the class described, the combination with movable staple driving means and cooperating staple clinching means, of an

elongated arm supported at one side of the driving and clinching means for rotation about an axis extending longitudinally thereof and for endwise movement, said arm having a slotted nose portion adapted to be interposed between the driving and clinching means to receive the edge of a piece of fabric, means for rotating said arm to form a fold in the fabric, an actuator operable to advance the staple driving means toward the staple clinching means to staple the fold to the body of the fabric, and cam means operated by said actuator for imparting endwise movement to said arm to withdraw the nose portion thereof from the fold before the stapling operation takes place.

6. In a machine of the class described, in combination, an elongated arm having a nose portion slotted to receive the edge of a piece of fabric, means supporting said arm for rotation about an axis extending longitudinally of the arm, means yieldably holding the arm in a predetermined position for the reception of the piece of fabric, and means for rotating the arm from said predetermined position through an angle of approximately two hundred and seventy degrees to form a generally wedge-shaped fold in the fabric.

7. In a machine of the class described, in combination, an elongated arm having a nose portion slotted to receive the edge of a piece of fabric, means supporting said arm for rotation about an axis extending lengthwise of the arm, means yieldably holding the arm in position for the reception of the piece of fabric, means for rotating the arm from said position through a predetermined angle to form a generally wedge-shaped fold in the fabric, and means for securing the folded portion to the body of the fabric.

8. In a machine of the class described, in combination, an elongated arm having a nose portion slotted to receive the edge of a piece of fabric, means supporting said arm for rotation about an axis extending longitudinally of the arm, means yieldably holding the arm in a position for the reception of the piece of fabric, means for rotating said arm away from said position through a predetermined angle to form a generally wedge-shaped fold in the fabric, means for holding an auxiliary part at one side of the fabric adjacent the fold, and means for securing the folded portion and the body of the fabric to said part.

9. In a machine of the class described having a movable stapling head and an opposed die unit cooperating with the head, the combination of an elongated arm rotatable about an axis extending longitudinally thereof and shiftable endwise toward and from the die unit, said arm having its nose portion slotted to receive the edge of a piece of fabric, means for holding the arm in a retracted position with its nose portion disposed at one side of the head and the die unit, means for shifting said arm to a position in which its nose portion is interposed between the head and the die unit, means operable to rotate said arm through a predetermined angle to form a fold in the edge of the fabric, means for moving the stapling head to clamp the folded fabric against the die unit, and means operable to impart endwise movement to said arm to withdraw the nose portion thereof from the fold and to drive a staple through the fold and body portion of the fabric.

10. In a machine of the class described having a movable stapling head and an opposed die unit cooperating with the head, the combination of an elongated arm supported for rotation about

an axis extending longitudinally thereof, said arm also being supported for endwise movement and for pivotal movement in a vertical plane about an axis perpendicular to the axis of rotation, a nose portion for said arm slotted to receive the edge of a fabric strip, means yieldably holding said arm in an inactive position with the nose portion disposed substantially above the die unit and at the rear of the staple head, actuating means operable initially to swing said arm about its pivot to position the nose portion above and closely adjacent the die unit for receiving the fabric strip and then to rotate the arm about its axis to form a fold in the strip, and other operating means operable initially to impart endwise movement to the arm to withdraw the nose portion from the fold and to operate the stapling head to drive a staple through the folded strip.

11. A machine of the class described comprising, in combination, a relatively thin, flat, elongated arm having a nose portion slotted to receive the edge of a piece of fabric, a housing supporting said arm for rotation about an axis extending longitudinally of the arm, means supporting said housing for pivotal movement about an axis extending transversely of the axis of said arm, means yieldably holding said housing in an inactive position with the side edges of said arm disposed in a substantially vertical plane, an actuating means operable initially to swing the housing about its pivot from said inactive position to present the nose portion of the arm in a position to receive the piece of fabric and then to rotate the arm about its longitudinal axis to form a fold in the fabric.

SERAPHINE F. BAUWENS.
